UNITED STATES PATENT OFFICE.

GILBERT L. BAKER, OF OAKLAND, CALIFORNIA.

GLARE SHIELD FOR ELECTRIC LAMPS.

Application filed September 15, 1926. Serial No. 135,623.

This invention relates to glare shields for electric lamps in general and particularly for use in connection with the headlights of vehicles.

5 One of the objects of the invention is the provision of a glare shield for application directly against the bulb of an electric lamp and held in place on the latter through the yielding pressure of a resilient bulb-engaging means to which the shield is attached, and to embody in the said means a novel form of construction and arrangement of parts whereby a positive retention of the shield relatively to the bulb may be maintained, the improved device also permitting ready application and removal of the shield relatively to the bulb.

The present invention is an improvement on the construction of a similar device disclosed by my pending application Serial No. 90,184, filed February 23, 1926, and the improved features will be more fully herein-after described and claimed.

In the drawing:

25 Fig. 1 is a side elevation of an electric lamp bulb and socket, showing the improved glare shield and holding means therefor applied in operative position;

30 Fig. 2 is a similar view, showing the glare shield and supporting means therefor detached and partially removed from the bulb;

35 Fig. 3 is a front elevation of the improved glare shield, showing the supporting and attaching means therefor mainly in dotted lines;

Fig. 4 is a rear elevation of the improved glare shield and supporting or retaining means therefor; and

40 Fig. 5 is a perspective view of the glare shield and improved supporting and applying means and looking towards the rear of the shield.

The numeral 5 designates the glare shield, which may be formed of transparent, translucent or opaque material, preferably of disk form and applicable against the bulb tangentially of the longitudinal axis thereof. The shield is supported by means which solely engage the bulb 6 of the electric lamp and 50 comprises opposed clasps or embracing members generally and respectively designated 7 and 8. The clasps 7 and 8 are identical in structure and are preferably formed of resilient wire or lengths of material having 55 the least width possible so as to effectively serve their purpose, and said clasps coact

with the bulb of the electric lamp from opposite sides of the latter. Each of the clasps is preferably formed from a single length of resilient wire bent into a substantial 60 U-shape and embodying a pair of longitudinally convex limbs or arms 9 continuous at the rear with eyes 10 connected by transverse members 10^a, which also continue from the eyes between the rear extremities of the 65 limbs or arms 9 and are bent or curved in arched formation, the two members 10 of the respective clasps 7 and 8 being curved in reverse directions so as to conform to the contour of the rear portion of the bulb 6 of 70 the electric lamp. The limbs or arms 9 slightly diverge in a forward direction and are continued into substantially right-angular straight shield-engaging legs 11, terminating in hooks 12 to closely fit over the 75 periphery of the shield 5 and terminally bear against the front side of the latter. The securing legs 11 continuous with the limbs or arms of the clasp 7 are reversed relatively to the similar legs of the clasp 8, or, for 80 the purpose of illustration, the legs 11 continuous with the arms 9 of the clasp 7 have a downward trend and the legs 11 continuous with the arms 9 of the clasp 8 project upwardly, both sets of legs being held in 85 parallelism by cross connectors 13 terminating in eyes 14 through which the legs 11 of both clasps extend. The cross connectors 13 with their eyes 14 are located close to the bends 15 between the limbs or arms of the 90 two clasps and the said legs, and a central clear space, as at 16, is thus provided at the rear side of the shield 5 to receive the front convex extremity of the bulb 6 of the electric lamp. The connectors 13 with their eyes 95 14 are movable relatively to the legs 11 and maintain the latter in close parallel relation and also operate to draw the terminal hooks 12 in close association with the periphery of 100 the glare shield 5, and by this means the shield is immovably held to practical operating position without penetrating the same for the purpose of securing the arms 9 thereto, as in the prior structure disclosed by my pending application hereinbefore 105 specified.

The securement of the arms 9 and the legs 11 over the bulb 6 is, in the present instance, rendered advantageously effective by connecting to the eyes 10 of the arms 9 of the upper clasp 7, for instance, catches 17 which are formed with eyes 18 at their upper ends 110

for movable association with the eyes 10 and have a series of notches 19 formed in their inner opposing edges fully to the free terminals thereof, for detachable engagement 5 and adjustment with relation to the eyes 10 of the arms 9 of the lower clasp 8. These catches 17 operate to draw the arms 9 of the opposed clasps 7 and 8 inwardly over and in tight relation to the rear reduced 10 portion of the bulb 6 and said catches also provide for applying the improved securing means for the shield 5 to bulbs of different 15 dimensions. The catches 17 may be readily attached to the lower eyes 10 and quickly detached from said latter eyes in applying and removing the improved structure to an electric lamp bulb. A further feature of structure in relation to the arms 9 is the lateral or outward deflection of the said 20 arms as clearly shown by Fig. 4. This lateral bent formation of the arms provides for firmly engaging the bulb 6 at such points as will be most effective in preventing the attaching means for the glare shield from 25 loose movement or the least displacement especially when the catches 17 are secured as shown by Fig. 4.

The upper and lower clasps with the catches 17, legs 11 and connectors 13 form 30 a cage embodying, in accordance with the features of construction heretofore explained and shown in the drawing, yielding and adjustable characteristics of advantage in applying the said cage to the bulb of an electric light and also for immovably holding the shield 5 in engagement with the said cage.

In its preferred use, the present invention provides an advantageous adjunct to an 40 automobile headlight, the glare shield softening or inhibiting the direct unreflected rays of the bulb and avoiding objectionable glare, which is the primary cause of many accidents. The improved glare shield with 45 its supporting cage also has the further advantage in that its use involves no change or alteration in existing headlight constructions, and it may be readily applied to or removed from the bulb in an expeditious 50 manner, and through its resilient engagement with the bulb, it maintains a permanent position despite vibration of the vehicle. The improved attachment may be manufactured at a comparatively small cost.

55 It will be understood that changes in the proportions, general dimensions and minor details of construction may be adopted without departing from the spirit of the invention or the scope of the appended claims.

60 What is claimed as new is:

1. A glare shield device including a glare inhibiting member and means for yieldably holding said member against an electric lamp bulb and comprising upper and lower 65 clasps with front angular extremities, ter-

minating in hooks embracing the periphery of the said member and independent adjustable catch devices for holding the clasps in engagement with the light bulb.

2. A glare shield device including a glare 70 inhibiting member and means for yieldably pressing said member against an electric lamp bulb and consisting of upper and lower clasps to embrace the bulb, the said clasps having forward angular means for engaging 75 the periphery of the member and rear adjustable catch devices for separably connecting the two clasps.

3. A glare shield device including a glare 80 inhibiting member and means for yieldably pressing said member against an electric light bulb consisting of a cage for embracing the bulb and having means at the forward portion thereof for removably engaging 85 different parts of the periphery of the member and also rear clasp devices for adjustably drawing the rear portions of the cage inwardly against the bulb.

4. A glare shield device including a glare 90 inhibiting member and a resilient supporting cage therefor shaped to embrace an electric lamp bulb and yieldably pressing said member against the bulb, the cage having rear independent pivotally mounted catch members 95 adjustably holding opposing parts thereof in close association with the lamp bulb.

5. A glare shield device including a glare 100 inhibiting member and a resilient supporting cage therefor shaped to embrace an electric lamp bulb and yieldably hold the said member against the forward extremity of the bulb, the cage comprising upper and 105 lower clasps with forward reversely and angularly bent legs terminating in hooks to engage different portions of the periphery of the member, the said legs being provided with independent pivoted catch means for the said legs to effect a tight association 110 thereof with the said glare inhibiting member.

6. A glare shield device including a glare 115 inhibiting member and a resilient supporting cage therefor shaped to embrace an electric lamp bulb and yieldably hold the said member against the forward extremity of the bulb, the cage comprising upper and lower clasps with forward reversely and angularly bent legs terminating in hooks to engage different portions of the periphery of the member, the said legs being provided with connecting means for effecting a tight association thereof with the said glare inhibiting member, the rear portions of the clasps having adjustable catches to separably connect the rear extremities of the clasps and hold the cage in positive association with the bulb and also provide for applying the cage and member to bulbs of different dimensions.

7. A glare shield device including a glare inhibiting member, a supporting cage therefor including resilient clasps having front reversely angularly bent legs terminating in hooks to embrace different portions of the periphery of the said member, and independent pivoted means attached to the rear extremities of the respective clasps for separably and adjustably securing the said 10 clasps relatively to the rear portion of an electric lamp bulb.

8. A glare shield device including a glare inhibiting member, a supporting cage therefor including opposed resilient clasps having front, reversely bent, angular legs ter-

minating in hooks to embrace different portions of the said member on opposite sides of the center of the latter, the clasps being adapted to embrace an electric lamp bulb and having cross members at their rear extremities and also catches to adjustably hold the said rear extremities and the cage as a whole in positive applied position relatively to the electric lamp bulb, the glare inhibiting member being yieldingly held 25 against the front extremity of the bulb.

In testimony whereof I have hereunto set my hand.

GILBERT L. BAKER.
